DESIGN FOR A FLOWER HOLDER

Golden S. Bowerfind, Norfolk, Va.

Application February 19, 1947, Serial No. 137,020

Term of patent 14 years

(Cl. D35—3)

To all whom it may concern:

Be it known that I, Golden S. Bowerfind, a citizen of the United States, residing at Norfolk, in the county of Norfolk and State of Virginia, have invented a new, original, and ornamental Design for a Flower Holder, of which the following is a specification, reference being made to the accompanying drawing, forming a part thereof.

In the drawings:

Fig. 1 is a side elevation of a flower holder embodying my new design; and

Fig. 2 is a perspective view thereof.

I claim:

The ornamental design for a flower holder, substantially as shown.

GOLDEN S. BOWERFIND.
